UNITED STATES PATENT OFFICE

CHARLES JAMES BRADBURY, OF BOSTON, ASSIGNOR OF ONE-HALF TO
JOHN H. HORNE, OF LAWRENCE, MASSACHUSETTS.

DEVICE FOR GRINDING ROLL-BARS.

SPECIFICATION forming part of Letters Patent No. 291,469, dated January 1, 1884.

Application filed March 15, 1883. Renewed November 26, 1883. (No model.)

To all whom it may concern:

Be it known that I, CHARLES JAMES BRADBURY, a citizen of the United States, residing at Boston, in the county of Suffolk and State of Massachusetts, have invented certain new and useful Improvements in Devices for Grinding Roll-Bars; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to means for enabling the grinding or "truing up" of the "rolls" of paper-pulp engines.

It is often necessary to supply the "rolls," so called, of paper-pulp engines with new grinding knives or "bars" in place of worn ones removed, and of necessity the edges of these knives project to varying degrees beyond the circumference of the roll and must be reduced to a uniform depth. In other words, the periphery of the roll must be ground down to a true circle.

As before premised, I employ a device constructed as hereinafter set forth, especially adapted to the purpose, and capable of being readily inserted and removed, and requiring no "boxing up" of the roll.

The drawings accompanying this specification represent in Figure 1 an isometric elevation of the device containing my invention. Fig. 2 in such drawings is a longitudinal vertical section.

In carrying out my invention, I provide a

box or trough, C, of cast-iron, of a length somewhat greater than that of the roll to be ground and of a width sufficient to contain enough 40 abrading materials to exert the necessary grinding action upon the roll—say of an inside measurement of about five inches. The interior of the box C is filled with a solid substance, D, composed of emery or other durable abrasive material.

When a roll is to be ground, it is raised, the bed-plate removed, and the box C deposited in place of such bed-plate. The roll is then put in rotation and lowered by degrees upon the 50 grinding material in the box C until the arched surface of the roll is true, the tub in which box C is set containing sufficient water to cover the trough C, to prevent heating of the knife-bars during said grinding operation. It is not 55 essential that the entire depth of the box C be filled with the grinding substance D. In point of fact, such substance may be comparatively shallow, and the box cast with a pocket in its upper part to receive it, as shown in the drawings at a. In this case the sides or lips b b, supporting said box or pocket a, are to be strengthened with cross-ribs c c, &c.

I claim—

The trough or box C, having lips b and 65 cross-ribs c, and containing abrading material D, for the purpose set forth.

In testimony whereof I affix my signature in presence of two witnesses.

CHARLES JAMES BRADBURY.
